United States Patent Office

Des. 186,402
Patented Oct. 20, 1959

186,402

LIGHTER OR SIMILAR ARTICLE

John A. Goddard, Cobham, England, assignor to Ronson Corporation, Woodbridge, N.J., a corporation of New Jersey

Application December 9, 1958, Serial No. 53,706

Claims priority, application Great Britain
October 29, 1958

Term of patent 14 years

(Cl. D48—27)

Fig. 1 is a perspective view of a lighter or similar article, showing my new design;

Fig. 2 is a perspective view thereof as seen from the opposite side of Fig. 1;

Fig. 3 is an elevational view thereof as seen from the opposite side of Fig. 1;

Fig. 4 is a top plan view thereof; and

Fig. 5 is a perspective view thereof with the cover in raised position, certain of the conventional parts being shown in broken lines.

The dominant features of my design reside in the portions shown in full lines.

I claim:

The ornamental design for a lighter or similar article, as shown and described.
